UNITED STATES PATENT OFFICE.

FRANK W. HUMPHREYS, OF OCEAN CITY, NEW JERSEY.

EXTENSION PLANE.

Application filed August 3, 1922. Serial No. 579,316.

To all whom it may concern:

Be it known that I, FRANK W. HUMPHREYS, a citizen of the United States, residing at Ocean City, in the county of Cape

5 May and State of New Jersey, have invented certain new and useful Improvements in Extension Planes, of which the following is a specification.

My invention relates to wood-working 10 tools and more particularly to planes.

The object of the invention is to provide an attachment of simple construction by which a short plane may be equipped with a long detachable face plate and thereby 15 perform the function of a longer plane.

These objects, and other advantageous ends which will be described hereinafter, I attain in the following manner, reference being had to the accompanying drawings 20 in which

Figure 1 is a plan view of my attachment with a plane secured therein,

Figure 2 is a sectional elevation of the device as shown in Figure 1, taken on the 25 line 2—2 of Figure 1,

Figure 3 is a vertical sectional view taken on the line 3—3 of Figure 2,

Figure 4 is a vertical sectional view taken on the line 4—4 of Figure 2,

30 Figure 5 is a plan view of the shoe forming the improvement, and

Figure 6 is a side elevation of the device as shown in Figure 5.

In the drawings, the attachment is shown 35 as consisting of a shoe having a face plate 7 and sides 8. The shoe is of substantially channel-shape cross section and has a slot 9 in the face plate for receiving the bit or blade 10 of an ordinary plane 11.

40 In order to secure the plane 11 in position, the opposite sides of the shoe are provided near each end with opposed longitudinal slots 12 flush with the top surface of the intermediate body portion or face

45 plate of the shoe. Cross bars 13 have reduced ends 14 slidably in slots 12 and each cross bar is adjustably secured in position by a pair of set screws 15 which engage the bottom of the shoe and force the reduced 50 ends of the cross bars against the top walls of slots 12.

Angular locking bars 16 are supported on each cross bar at right angles thereto, or longitudinally of the shoe, and their inner 55 ends are turned downwardly as indicated at 17 to contact with the face plate of plane

11. The locking bars 16 have longitudinal slots 18 and thumb screws 19 are disposed through these slots and threaded in vertical apertures midway of the ends of cross 60 bars 13.

In applying a plane to the shoe, cross bars 13 and locking bars 16 are first moved outward so that plane 11 will be accommodated between the inner ends of bars 16. By unseating screws 15 and relieving the binding engagement of ends 14 against the top walls of slots 12, cross bars 13 may be moved outward in slots 12. By loosening screws 19, bars 16 may be moved outward, by reason 65 of slots 18. Screws 15 are tightened before or after adjustment of locking bars 16 and when plane 11 has been placed in the shoe, the screws are tightened and ends 17 of bars 16 clamped firmly against plane 11. This 70 adjustment facilitates the application and removal of the plane, and the fastening means insures positive retention of the parts in assembled relation.

When a plane is applied to the shoe as described, the length of the plane will be extended so as to convert a smaller plane into a larger plane, such as a smoothing plane into a fore plane, or a fore plane into a jointer plane. After the cross bars 13 have 80 been adjusted and anchored by set screws 15, the angular locking bars 16 are adjusted so that downturned ends 17 will engage the top of plane 11 and then tightening thumb screws 19, locking bars 16 will be 85 held against movement and the handle and blade of plane 11 will serve their usual functions when the plane is in use as thus converted. It is to be understood that the device may be adjusted to accommodate 90 different sized planes or those varying in length.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly 100 come within the scope of the appended claims.

Having thus described my invention, what I claim as new and desire to secure by Letters Patent is:—

110 1. An attachment for planes comprising a shoe adapted to receive a plane; ad-

- justable clamping means for securing the plane in operative position in the shoe; and means for permitting movement of said clamping means to various adjusted 5 positions on said shoe.
2. An attachment for planes comprising a shoe adapted to receive a plane; and clamping means on said shoe, said clamping means being arranged to be moved to various adjusted positions for accommodating 10 planes of various sizes.
3. An attachment for planes comprising a shoe adapted to receive a plane; supporting means mounted adjacent each end of 15 said shoe and capable of longitudinal movement to various adjusted positions; and clamps for engaging said plane, said clamps being longitudinally adjustable on said supporting means.
4. A convertible shoe for planes comprising a substantially channel-shaped member having sides with slots; cross bars longitudinally adjustable in the slots, and longitudinal clamping members adjustably 20
- carried by the cross bars and having parts 25 at their inner ends to clamp a plane against the shoe.
5. An attachment for planes comprising a substantially channel-shaped shoe having opposed slots in its sides near each end; cross bars having their ends slidable in the slots; means to hold the cross bars in adjusted positions in the slots; locking bars having slotted portions resting upon the cross bars and downwardly extending portions at their inner ends adapted to engage a plane placed in the shoe, and clamping means carried by the cross bars and disposed through the slots of the locking bars to hold the locking bars in adjusted positions. 30 35 40

In testimony whereof I have signed my name to this specification in the presence of two subscribing witnesses.

FRANK W. HUMPHREYS.
